(57) **CLAIM**

The ornamental design for a fluid monitor, as shown and described.

DESCRIPTION

FIG. 1 is an elevation view of the left side of a first variation of the fluid monitor;

FIG. 2 is an elevation view of the front of the first variation of the fluid monitor;

FIG. 3 is an elevation view of the right side of the first variation of the fluid monitor;

FIG. 4 is an elevation view of the back of the first variation of the fluid monitor;

FIG. 5 is an isometric view, from the top front, of the first variation of the fluid monitor including a solar panel;

FIG. 6 is an isometric view, from the bottom back, of the first variation of the fluid monitor;

FIG. 7 is a plan view of the top of the first variation of the fluid monitor including the solar panel;

FIG. 8 is a plan view of the bottom of the first variation of the fluid monitor;

FIG. 9 is an elevation view of the left side of a second variation of the fluid monitor;

FIG. 10 is an elevation view of the front of the second variation of the fluid monitor;

FIG. 11 is an elevation view of the right side of the second variation of the fluid monitor;

FIG. 12 is an elevation view of the back of the second variation of the fluid monitor;

FIG. 13 is an isometric view, from the top front, of the second variation of the fluid monitor;

FIG. 14 is an isometric view, from the bottom back, of the second variation of the fluid monitor;

FIG. 15 is a plan view of the top of the second variation of the fluid monitor; and,

FIG. 16 is a plan view of the bottom of the second variation of the fluid monitor.
